MEANS FOR HANDLING AND TRANSPORTING PULVERULENT, GRANULAR, AND LIKE MATERIAL

Miles B. Squire, Jr., Bronx, N. Y., assignor to Kennedy-Van Saun Mfg. & Eng. Corporation, New York, N. Y., a corporation of Delaware

Application March 30, 1949, Serial No. 84,422

1 Claim. (Cl. 302—25)

1

This invention relates to means for handling and transporting pulverulent material, such as flour, pulverized coal and cement, granular material, such as rye, wheat, oats, corn and flaxseed, and other material, such as slimes or slurries and concrete. Said means include a pressure container for the material having a discharge outlet at the bottom thereof and arranged with means to admit fluid under pressure, such as steam or air, into the container and the discharge outlet to aerate and place the material in the container under pressure and discharge it through the discharge outlet. It is customary to transport the material discharged from the container to a depository or place of use for said material through a transport conduit.

It has been found that it is only possible to transport said material discharged from the container by the fluid pressure admitted to the container and the discharge outlet for a distance not greater than 150 feet.

It is the object of the invention to provide means to increase the buoyancy of the material being discharged from the container and increase the distance in which the material is transported from the container to a depository or place of use for the material without the aid of motors, screw conveyers or boosters in the transport conduit.

This means comprise a conical casing having the larger end mounted in communication with the discharge outlet of the container and the smaller end connected in communication with the transport conduit, and series of spaced nozzles mounted in the larger end of the casing to direct a conical stream of fluid pressure toward the transport conduit and connected in communication with the source of fluid pressure for the container.

Other objects and advantages of the invention will be disclosed in the following description of the invention.

In the drawings accompanying and forming a part of this application,

Figure 1 is a sectional view of the bottom portion of the pressure container having the material discharge outlet arranged with the means to increase the buoyancy and the distance of travel of the discharged material.

Figure 2 is a fragmentary view of the improved means to show a handle attached thereto to facilitate the mounting thereof on the discharge outlet of the container.

Figure 3 is a sectional view of said means to show the construction thereof.

2

Figure 4 is a partial view looking at the larger end of the conical casing.

Figure 5 is an elevational view of a pressure container connected in communication with a depository for the material discharged from the container and showing the embodiment of the invention incorporated in said connection.

The invention is shown in the accompanying drawings in combination with a pressure container 6 having a material filler opening at the upper portion adapted to be pneumatically sealed by a closure, as indicated at 7 in Figure 5, and a hopper bottom, as shown at 8 in Figure 1. The hopper bottom is arranged with a material discharge member consisting of a cup member secured to said bottom and having a discharge conduit 10 connected at one end in communication with said cup member and hopper bottom. The opposite end of the discharge conduit is extended to an opening 11 in a lower extension 12 of the side wall of the container. Said lower extension 12 supports the container upon a suitable base 13 adapted to mount the container on a vehicle, such as a railroad flat car, a motor truck or barge, or on a permanent foundation if desired.

Fluid pressure, such as compressed air or steam, is delivered from a suitable source of supply, not shown, to the top and hopper bottom of the container to agitate and discharge the material from the container through the discharge conduit. The fluid pressure is delivered from the source of supply through a conduit, partly shown at 14 in Figure 1, connected at one end to the source of supply and connected at the opposite end to a pipe portion 15 extending through the opening 11 and connected to a pipe portion 16 mounted on the base 13, as shown at 17 in Figure 1. The pipe portion 16 is provided with a shut-off valve shown in a general way at 18 in Figure 1 and a lateral extension 19 from said valve connected in communication with a conduit 20 extended through the lower extension 12 of the side wall of the container and in an upward direction along said side wall to a fluid pressure inlet in the top wall of the container, shown in a general way at 21 in Figure 5, to exert pressure on the top of the material in the container and force said material toward the hopper bottom 8 and discharge conduit 10. The lateral pipe extension 19 is also connected in communication with a series of nozzles 22 mounted in the hopper bottom 8 to spray fluid pressure into the hopper bottom 8 to aerate and wash the material from the wall

of the hopper bottom. The lateral pipe extension 19 is further connected in communication with a series of nozzles 23 mounted in the cup member 9 to spray fluid pressure into said cup member and further agitate the material in the cup member. The material in the cup member is forced into the discharge conduit 10 by the fluid pressure from the pipe extension 19 by connecting said pipe extension in communication with a nozzle 24 mounted in the cup member 9 in line with the outlet thereof, as shown in Figure 1.

The material discharge conduit 10 is connected in communication with a place of use or a depository for said material and shown in Figure 5 to be a storage bin 25 connected in communication with the free end of the discharge conduit 10 through a transport conduit 26.

It has been found that the fluid pressure delivered to the container 6 from the pipe extension 19 was only able to transport the discharged material for a maximum distance of 150 feet from the container.

Means have been provided to increase this distance in which the material is transported from the container 6 to the bin 25 without the use of additional means of propulsion than that provided by the fluid pressure delivered to the container by the conduit 14. Said means comprises a conical casing 27 having a diameter at the smaller end substantially equal to the diameter of the conduits 10 and 26. The larger end of said casing is provided with an annular series of nozzles 28 spaced equidistantly apart in an annular plate 29 secured to the larger end of the conical casing 27 as by welding 30 and having an opening 31 corresponding to the diameter of the smaller end of the conical casing, as shown in Figure 3. The nozzles 28 are secured in equidistantly spaced holes 32 in the plate by welding 33 with the nozzles extending at an angle diverging from the side wall of the casing 27, so that the nozzles will eject streams of fluid pressure in paths converging at a point beyond the smaller end of the conical casing 27 and substantially in the center of the stream of travel of flow of the material in fluid suspension in the conduits 10 and 26. The nozzles 28 communicate with an annular groove 34 in the outer face of the plate 29 and communicating with the holes 32. The fluid pressure is supplied to the nozzles 28 and annular groove 34 from the supply conduit 14 through a hose 35 connected at one end in communication with a coupling member mounted in communication with the pipe portion 15 and arranged with a valve mechanism and a check valve, as indicated in a general way at 36 and 37, respectively, to shut-off and control the flow of fluid pressure from the source of supply to the nozzles 28. The opposite end of the hose 35 is connected in communication with a coupling member 38 mounted on a nipple 39 secured by welding 40 to an annular plate 41 having an opening 42 therethrough communicating with the nipple 39 and the annular groove 34, as shown in Figure 3. The annular plate 41 is secured by welding 43 to a tubular member 44 having a flange at the opposite end in the form of an annular plate 45 secured to said end of the tubular member 44 by welding 46. The tubular member 44 and annular plates 41, 45 form a coupling member 44 having flanges 41, 45 at the opposite ends. Said coupling member is secured to the conical casing 27 with the opening 42 in register with

a portion of the groove 34 and the remaining portion of said groove closed by the flange 41. This is accomplished by bolts 59 engaged in equidistantly spaced holes in the flange 41 and screw threaded in corresponding holes 60 in the annular plate 29.

The larger end of the conical casing 27 is removably connected to the free end of the discharge conduit 10 by the coupling member 44 having the flange 45 secured to a flange on the free end of the discharge conduit 10 in the form of an annular plate 47 screw threaded on the discharge conduit 10, as shown in Figure 3. Bolts 48 are secured in aligned openings in the flanges 45 and 47 with the openings in the flange 45 reinforced by washers 49 welded thereto.

The smaller end of the conical casing 27 is adapted to be connected in communication with the transport conduit 26 by providing a flange on said smaller end in the form of a flat ring 50 engaged on a straight wall end portion 51 at the smaller end of the conical casing and the flange secured to the casing by welding 52. The ring flange 50 is arranged with holes reinforced in the same manner as the openings in flange 45, as shown at 53. The flange 50 is removably connected to a flange 54, in the form of a plate screw threaded on one end of a straight wall coupling member 55, by bolts engaged and secured in corresponding holes in the flanges 50 and 54, as shown at 56 in Figure 3. The transport conduit 26, which is usually of flexible material, is slidably engaged on the free end of the coupling member 55 as shown in Figures 1 and 3.

To facilitate mounting and removal of the conical casing relative to the discharge conduit 10, said casing is provided with a handle in the form of a bar 57 mounted midway of the ends thereof on a leg portion of an angle bracket 58 secured at the other leg portion on the outer face of the flange 50, as shown in Figure 2.

In the operation of the device, the valves 18 and 36 are actuated to open position when it is desired to discharge material from the container, and which will cause a series of converging jets of fluid pressure from the nozzles 28 gradually intermingling with the flow of the fluid suspended material and greatly increasing the buoyancy of said material.

Having thus described my invention, I claim:

In means for handling and transporting pulviferulent, granular and the like material, a conduit for transporting such material in fluid suspension, a conical casing interposed in the conduit, and annular series of spaced nozzles mounted in the larger end of the casing and connected to a source of fluid pressure to direct an annular stream of fluid pressure about the flow of fluid suspended material in the conduit, and means to connect the larger end of the casing to a section of the conduit and mount the nozzles in the larger end of the casing comprising an annular plate having an annular groove in one face thereof and a series of holes communicating with the annular groove and opening to the other face of the plate for mounting the nozzles in said plate in communication with the annular groove and said plate secured to the larger end of the casing, and a second annular plate secured to the face of the first annular plate arranged with the annular groove to close said groove and having an opening therethrough communicating with the annular groove and arranged to be connected to the source of

2,673,125

5

fluid pressure and said second plate secured to the conduit section.

MILES B. SQUIRE, JR.
